CLAIM

The ornamental design for a mobile phone, as shown and described.

DESCRIPTION

FIG. 1 is a front perspective view of a mobile phone showing our design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of portion 9 of the mobile phone in FIG. 1.

FIG. 10 is an enlarged view of portion 10 of the mobile phone in FIG. 2.

FIG. 11 is an enlarged view of portion 11 of the mobile phone in FIG. 2; and,

FIG. 12 is an enlarged view of portion 12 of the mobile phone in FIG. 2.

The broken lines show portions of the mobile phone that form no part of the claimed design. The dot dash lines containing portions of the mobile phone in FIG. 1 and illustrated in enlarged views in FIG. 9 form no part of the claimed design. The dot dash lines containing portions of the mobile phone in FIG. 2 and illustrated in enlarged views in FIGS. 10 to 12 form no part of the claimed design.

1 Claim, 12 Drawing Sheets
